[57] CLAIM

The ornamental design for a bottle or similar article, substantially as shown and described.

DESCRIPTION

FIG. 1 is a front elevational view of a bottle or similar article showing my new design;

FIG. 2 is a bottom view thereof;

FIG. 3 is a side elevational view thereof, both sides being identical; and

FIG. 4 is a top plan view thereof.

The back of the bottle is plain and unornamented.
